GARMENT HANGER SUPPORTING MEANS

Abraham Levine, Elizabeth, N. J., assignor to
 Presto Lock Corporation, Garfield, N. J., a corporation of New Jersey

Application November 14, 1939, Serial No. 304,288

7 Claims. (Cl. 312—177)

This invention relates to improvements in garment carrying fixtures for use in luggage cases, wardrobe trunks and other garment storage compartments or spaces; and the invention has reference, more particularly, to novel extensible supporting means for holding removable garment hanger devices upon which garments are suspended for packing or storage.

The invention has for an object to provide novel garment hanger supporting means including a fixed section and a telescopically related, spring projected extensible section, together with novel manipulative releasable detent means for retaining the latter in collapsed or retracted relation to the former subject, upon release, to limited projected extension endwise therefrom, whereby a plurality of garment hangers, and the garments suspended therefrom, may be separated one from another to facilitate removal of a selected hanger and the garment carried thereby.

Other objects of this invention, not at this time more particularly enumerated, will be understood from the following detailed description of the same.

An illustrative embodiment of this invention is shown in the accompanying drawing, in which:

Fig. 1 is a fragmentary front elevational view of a garment carrying fixture equipped with the novel extensible garment hanger supporting means according to the invention; Fig. 2 is a vertical cross section, taken on line 2—2 in Fig. 1; Fig. 3 is a vertical cross section, taken on line 3—3 in Fig. 1; and Fig. 4 is a transverse sectional view, taken on line 4—4 in Fig. 3.

Similar characters of reference are employed in the above described views, to indicate corresponding parts.

In the illustrative form of the extensible garment hanger supporting means shown in the drawing, the same comprises a suitably shaped main section preferably formed by a sheet metal stamping which is folded upon itself to provide a hollow cylindrical fixed hanger bar support 5, having opposed casing sides 6 and 7 depending therefrom. Said casing sides 6 and 7 are respectively provided with inturned abutting marginal flanges 8 and 9, thus forming intermediate said casing sides, a relatively narrow internal housing chamber 10, communicative with the hollow interior of said fixed hanger bar support 5.

Telescopically slideable within the hollow interior of the fixed hanger bar support 5, for outward projection through the forward open end thereof, is an extensible hanger bar support 11. Said extensible support 11 comprises a cylindrical

tubular member formed at its rearward or inner end with stop lug means 12, to depend from the under side thereof into the upper portion of the narrow housing chamber 10. As thus disposed 5 said stop lug means 12 rides between the side walls 6 and 7 of said housing chamber 10 which serve as guides therefor during movements thereof consequent upon the longitudinal in and out movements of said extensible support 11. The 10 exteriorly projecting forward end portion of said extensible support 11 is provided with a diametrically enlarged terminal head, suitably formed and connected therewith. In the illustrative form thereof shown in the drawing, said 15 terminal head comprises a closure plug 13 which is entered in and affixed to the outer end portion of the extensible support 11. Said plug 13 is provided with a forwardly and axially-projecting stud 14 of reduced diameter, over which is engaged a terminal head disc 15, the latter being fixed in place by riveting over the free end portion of said stud 14, as shown at 16. If desired, an ornamental finishing element or cover shell 17 is secured over and around said disc 15 by a marginal bead 18 with which the same is provided, and which is turned over and engaged around the periphery of said disc 15.

The rearward end of said fixed hanger bar support 5 is provided with a suitably formed diametrically enlarged terminal head. As illustrative form of this terminal head as shown comprises, a head disc 19 having a central perforate hub portion 20 to seat in a rear end opening provided in the rear end wall 21 of said fixed hanger bar support 5. Secured within said fixed hanger bar support 5 to extend forwardly from the rearward end thereof, and also axially within the extensible support 11, is a spring carrier rod 22. In order to affix said rod 22 in place, and at the 30 same time secure said head disc 19 in assembled relation to the fixed hanger bar support 5, said rod is provided at its rearward end with an axially projecting stud 23 of reduced diameter, and over this stud is engaged a perforate keeper washer 24, one side of which abuts the shoulder provided at the juncture of said rod 22 and its stud 23, and the other side of which abuts the interior side of the rear end wall 21 of said fixed hanger bar support 5. The free end portion of 35 said stud 23 is projected outwardly through the perforate hub portion 20 of said head disc 19, being riveted over against the outer face thereof, as shown at 25, thus rigidly emitting both the head disc 19 and the spring carrier rod 22 in operative assembled relation to said fixed hanger

bar support 5. A spiral compression spring 26 is provided and so arranged that its rearward end portion is supported by said rod 22 and footed against the rear end portion of the support 5, while its forward end portion extends through said extensible support 11 into thrusting engagement with the closure plug 13 of the latter, so as to yieldably thrust said extensible support 11 to outwardly projected extension from the forward end of said fixed hanger bar support 5.

Manipulative releasable means is provided for holding the extensible support 11 retracted to normal collapsed relation to the fixed support 5. This means comprises a detent member 27, which is pivotally mounted on a fulcrum stud 28 affixed to and between the casing sides 6 and 7 within the housing chamber 10, so as to extend rearwardly through the interior of said chamber beneath the path of movement of said extensible support 11 as telescopically slideable within said fixed support 5. At its rearward free end, said detent member is provided with an upwardly projecting detent nosing 29 having a chamfer 30 at its inward side. Said detent member 27 is also shaped to provide, adjacent its forward pivoted end, an upwardly projected stop shoulder 31. Integrally formed in connection with said rearward free end portion of said detent member 27 is a downwardly and forwardly inclined cam arm 32.

The means for manipulating said detent member 27 comprises a push-plate 33 arranged within the housing chamber 10 below said detent member. Said push-plate is provided with a slot 34 to engage a stud 35 affixed to and between the casing sides 6 and 7, to thereby guide its movements. At its forward end, said push-plate is further provided with an exteriorly projecting push-piece 36 which extends outwardly through an opening 37 formed in the forward edge wall portion of said housing chamber. On the exterior end of said push-piece 36 is fixed a push-button or finger-piece 38. At its rearward or inner end, said push-plate 33 is provided with a projecting push-finger 39 which is opposed to the cam arm 32 of said detent member 27 for cooperation therewith. Indenting said push-plate 33 is a downwardly extending notch 40 to provide a shoulder 41.

Mounted on and around a stud 42 affixed to and between the casing sides 6 and 7, for location between the detent member 27 and the push-plate 33 is a spring member 43, the upper horizontal arm 44 of which yieldingly bears against the underside of said detent member 27 to swing the latter to normal upraised position, while the lower vertical arm 45 of said spring member enters said notch 40 of the push-plate 33 to yieldingly bear against the shoulder 41 so as to thrust said push-plate to normal outwardly moved position.

When the extensible support 11 is pushed back into the fixed support 5, which is the normal telescopically collapsed position thereof, its stop lug 12 rides over the chamfer 30 of the detent nosing 29, thus depressing the detent member 27, against the tension of spring arm 44, which thereafter swings upward to oppose said detent nosing 29 to the stop lug 12, thereby holding the extensible support 11 retracted within the fixed support 5 against the tension of the compressed spring 26 (as shown by full lines in Fig. 3).

When it is desired to release the extensible support 11 for outwardly extended projection from the fixed support 5, the operator presses

inwardly upon the push-button or finger-piece 38, thus transmitting through the push-piece 36 inward movement to the push-plate 33, against the tension of spring arm 45, thereby moving the push-finger 39 relative to the cam arm 32 of the detent member 27 to cause the latter to be depressed against the tension of spring arm 44. Such manual depression of the detent member 27 downwardly withdraws the detent nosing 29 from obstructing relation to the stop lug 12 of the extensible support 11, thereby freeing the latter subject to the outwardly thrusting effect of the spring 26, so that said extensible support 11 is projected outwardly from said fixed support to extended relation thereto (as shown by broken lines in Fig. 3).

The novel extensible garment hanger supporting means may be utilized as a single unit within a garment storage compartment or space, in which case the fixed support would be suitably mounted and secured in a stationary position within said storage compartment or space subject to removable application thereto of suitably shaped suspension hook means of garment hangers desired to be suspended therefrom. When used in wardrobe trunks, luggage cases and the like, the extensible garment hanger supporting means are preferably arranged in pairs, the members of which are laterally spaced apart for engagement by the hooked end portions 46 of a garment supporting bar 47, whereby the latter is removably supported in bridging relation to and between said members (see Fig. 1).

The novel extensible garment hanger supporting means is especially well adapted for use in connection with garment folding and carrying fixtures now extensively used in luggage cases, and which usually include side arms 48 pivotally attached by their inner ends to the luggage case so as to swing into and out of a compartment of the latter, such e. g. as the interior of the luggage case cover section. When used in this connection the supporting devices are employed in pairs, one thereof being affixed to the outer free end portion of each side arm 48 of the carrying fixture. To facilitate attachment to the fixture side arms 48, the housing chamber 10 is so formed in its lower portion as to provide an open neck portion 49 through which the free end portion of a side arm 48 may be passed to extend into the housing chamber interior so as to lie between the casing sides 6 and 7, being thereupon fixedly joined thereto by transverse fastening rivets 50. The extensible garment hanger supporting means as thus carried by the fixture side arms 48 are disposed in transversely spaced apart relation, and are joined together in such relation by a transverse tie or cross bar 51, which is provided at its ends with angular coupling lugs 52 adapted to respectively extend into the rearward portion of the respective housing chambers 10 so as to also lie between the casing sides 6 and 7, being fixedly joined thereto by transverse fastening rivets 53.

It will be obvious that when the extensible supports 11 are released and projected for outward extension from the forward ends of the fixed supports 5, so that a plurality of garment hanger bars 47 applied thereto may be moved outwardly onto the extensible supports 11 and thus separated one from another to give convenient access to a selected bar and garment carried thereby for either removal or deposit as the case may be. When, however, a plurality of bars 47, with garments suspended thereon, are

deposited upon and in supported relation to and between the supporting devices, the extensible supports 11 of the latter may thereupon be pushed into retained telescopically collapsed relation to the fixed supports 5, thereby moving the bars and suspended garments together ready for packing or storage in compactly related condition within the receiving space or compartment into which the carrying fixture may be folded.

From the above description it will be understood that a very simple, neat and effective extensible garment hanger supporting means for the purposes described is provided, wherein the control parts are fully enclosed and pocketed against relative disarrangement, while at the same time the enclosing means therefor assures that garments on the hangers suspended therefrom are guarded against contact or engagement with said control parts, and consequently 15 risk of catching, tearing or like injury to the garment material is eliminated.

I am aware that various changes could be made in the construction of the novel extensible garment hanger supporting means, and that many apparently widely different embodiments of the features of construction thereof could be made without departing from the scope of this invention as defined by the following claims. It is therefore intended that all matter contained 30 in the above description or shown in the accompanying drawing shall be interpreted as illustrative and not in a limiting sense.

I claim:

1. An extensible garment hanger supporting means comprising, a hollow casing having a cylindrical upper portion forming a fixed support, a spring projected extensible support telescopically slidably in said fixed support, said extensible support having a stop means on its inner end portion, a yieldable detent member pivotally mounted in said casing beneath said extensible support, said member having a nosing at its free end to engage said stop means for holding said extensible support retracted within said fixed support, a spring retracted push-plate means slidably mounted within said casing, said detent member having a cam arm engageable by said push-plate means for swinging said detent member so as to release its nosing from said stop means with consequent release of said extensible support for extended projection from said fixed support, and said push-plate means having a push-piece exteriorly projecting from said casing for manually actuating the same.

2. An extensible garment hanger supporting means comprising, a hollow casing having a cylindrical upper portion forming a fixed support, a spring projected extensible support telescopically slidably in said fixed support, said extensible support having a stop nosing on its inner end portion, a yieldable detent member pivotally mounted in said casing, said member having a nosing at its free end to engage said stop means for holding said extensible support retracted within said fixed support, said member also having a stop shoulder adjacent to its pivoted end to engage said stop means for limiting the extended projection of said extensible support, and manipulatable means mounted within said casing operative to move said detent member to release its nosing from said stop means with consequent release of said extensible support for extended projection from said fixed support, said manipulatable means having means exteriorly 75

projecting from said casing for manually actuating the same.

3. An extensible garment hanger supporting means comprising, a hollow casing having a cylindrical upper portion forming a fixed support, a spring projected extensible support telescopically slidably in said fixed support, said extensible support having a stop nosing on its inner end portion, a yieldable detent member pivotally mounted in said casing, said member having means at its free end to engage said stop nosing for holding said extensible support retracted within said fixed support, said member also having a stop shoulder adjacent to its pivoted end to engage said stop nosing for limiting the extended projection of said extensible support, a spring retracted push-plate slidably mounted within said casing, said detent member having a cam arm, said push-plate having a push-finger to engage said cam arm for the purposes described, and said push-plate having a push-piece exteriorly projecting from said casing for manually actuating the same.

4. The combination with laterally spaced side arms of a garment carrying fixture of extensible garment hanger bar supporting devices mounted thereon, each supporting device comprising a casing formed to provide a hollow cylindrical upper portion to serve as a fixed support and a relatively narrow housing chamber in communication with the interior of said fixed support to extend along and below the same, said housing chamber having a downwardly projecting open neck portion to receive a side arm of said fixture 35 for fixed attachment thereto, a spring projected extensible support telescopically slidably in said fixed support and having a stop member at its inner end portion to project into said housing chamber, releasable detent means mounted within said housing chamber for cooperation with said extensible support stop member, and means exteriorly projecting from said housing chamber for manipulating said detent means.

5. The combination with laterally spaced side arms of a garment carrying fixture of extensible garment hanger bar supporting devices mounted thereon, each supporting device comprising a casing formed to provide a hollow cylindrical upper portion to serve as a fixed support and a relatively narrow housing chamber in communication with the interior of said fixed support to extend along and below the same, said housing chamber having a downwardly projecting open neck portion to receive a side arm of said fixture 40 for fixed attachment thereto, a spring projected extensible support telescopically slidably in said fixed support and having a stop member at its inner end portion to project into said housing chamber, releasable detent means mounted within said housing chamber for cooperation with said extensible support stop member, and means exteriorly projecting from said housing chamber for manipulating said detent means.

6. The combination with laterally spaced side arms of a garment carrying fixture of extensible garment hanger bar supporting devices mounted thereon, each supporting device comprising a casing formed to provide a hollow cylindrical upper portion to serve as a fixed support and a relatively narrow housing chamber in communica-

cation with the interior of said fixed support to extend along and below the same, said housing chamber having a downwardly projecting open neck portion to receive a side arm of said fixture for fixed attachment thereto, a spring projected extensible support telescopically slideable in said fixed support and having a stop member at its inner end portion to project into said housing chamber, a yieldable detent member pivotally mounted in said housing chamber, said member having a nosing at its free end for cooperation with said extensible support stop member, said member also having a stop shoulder adjacent to its pivoted end to engage said stop member for limiting the extended projection of said extensible support, a spring retracted push-plate slidably mounted within said housing chamber, said detent member having a cam arm, said push-plate having a push-finger to engage said cam arm for the purposes described, and said push-plate having a push-piece exteriorly projected from said housing chamber for manually actuating the same.

7. The combination with laterally spaced side arms of a garment carrying fixture of extensible garment hanger bar supporting devices mounted thereon, each supporting device comprising a casing formed to provide a hollow cylindrical upper portion to serve as a fixed support and a

5 relatively narrow housing chamber in communication with the interior of said fixed support to extend along and below the same, said housing chamber having a downwardly projecting open neck portion to receive a side arm of said fixture for fixed attachment thereto, a spring projected extensible support telescopically slideable in said fixed support and having a stop member at its inner end portion to project into said housing chamber, a yieldable detent member pivotally mounted in said housing chamber, said member having a nosing at its free end for cooperation with said extensible support stop member, said member also having a stop shoulder adjacent to its pivoted end to engage said stop member for limiting the extended projection of said extensible support, a spring retracted push-plate slidably mounted within said housing chamber, said detent member having a cam arm, said push-plate having a push-finger to engage said cam arm for the purposes described, said push-plate having a push-piece exteriorly projected from said housing chamber for manually actuating the same, and a transverse tie-bar having at its ends angular coupling lugs respectively entered and affixed within the housing chambers of said respective supporting devices.

ABRAHAM LEVINE.
